(57) **CLAIM**

The ornamental design for a display screen with an animated graphical user interface, as shown and described.

DESCRIPTION

FIG. 1 is a front view of a first image of a display screen with an animated graphical user interface.

FIG. 2 is a front view of a second image of the display screen with the animated graphical user interface.

FIG. 3 is a front view of a third image of the display screen with the animated graphical user interface.

FIG. 4 is a front view of a fourth image of the display screen with the animated graphical user interface.

FIG. 5 is a front view of a fifth image of the display screen with the animated graphical user interface.

FIG. 6 is a front view of a sixth image of the display screen with the animated graphical user interface.

FIG. 7 is a front view of a seventh image of the display screen with the animated graphical user interface; and, FIG. 8 is a front view of an eighth image of the display screen with the animated graphical user interface.

The outermost broken lines depicting an electronic device are included to illustrate environmental subject matter and form no part of the claimed design. The remaining broken lines illustrate a display screen and portions of the animated graphical user interface that form no part of the claimed design. The light gray pill button features shown in FIG. 7 form part of the claim design as shown.

1 Claim, 8 Drawing Sheets
